US00D993381S

(12) **United States Design Patent** (10) **Patent No.:** **US D993,381 S**
(45) **Date of Patent:** **** Jul. 25, 2023**

(54) **FAN**

(71) Applicant: **ShenZhen TopSharp Precision Electronics Co., Ltd.**, Shenzhen (CN)

(72) Inventor: **Wenlong Xu**, Shenzhen (CN)

(73) Assignee: **SHENZHEN TOPSHARP PRECISION ELECTRONICS CO., LTD.**, Shenzhen (CN)

(**) Term: **15 Years**

(21) Appl. No.: **29/777,045**

(22) Filed: **Apr. 2, 2021**

(30) **Foreign Application Priority Data**

Mar. 12, 2021 (CN) 202130134913.3

(51) **LOC (14) Cl.** **23-04**

(52) **U.S. Cl.**

USPC **D23/382**

CLAIM

The ornamental design for a fan, as shown and described.

DESCRIPTION

FIG. 1 is a perspective view of a fan showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a fan showing my new design where the fan is in a first configuration of use;

FIG. 10 is a perspective view of the fan where the fan is in a second configuration of use;

FIG. 11 is a perspective view of the fan where the fan is in a third configuration of use;

FIG. 12 is an exploded perspective view of the fan; and,

FIG. 13 is a perspective view of the fan where the fan is in a fourth configuration of use.

The broken lines in the drawings depict portions of the fan that form no part of the claimed design.

1 Claim, 13 Drawing Sheets
